UNITED STATES PATENT OFFICE.

KATSUSABURO USUI, OF NEMUROMACHI, HOKKAIDO, JAPAN.

PROCESS FOR CANNING CRABS, LOBSTERS, AND THE LIKE.

1,172,076.

Specification of Letters Patent. Patented Feb. 15, 1916.

No Drawing.

Application filed May 29, 1915. Serial No. 31,230.

To all whom it may concern:

Be it known that I, KATSUSABURO USUI, merchant, a subject of the Emperor of Japan, residing in No. 1, 4-Chome, Urra-
5 dori, Oaza Kiotakacho, Nemuromachi, Hok-
kaido, Empire of Japan, have invented cer-
tain Improvements in Processes for Can-
ning Crabs, Lobsters, and the like, of which
the following is a specification.

10 This invention has reference to an im-
proved process for canning crabs, lobsters,
and the like, which consists in first strip-
ping off the shell or carapace and termi-
nally operating upon each leg of the said
15 crabs, lobsters, and the like, provided such
operation should be performed while they
are still living, so as to cause the blood and
lymph circulating thereof to flow out spont-
aneously through the point or points of
20 operation, and subsequently treating the
same in the manner usually practised in the
crustacean canning industry; and has for
its object to render the process more ex-
peditious, considerably cheaper and more
25 reliable in effect without having the disad-
vantage of discoloring the products that are
to be used for the consumption of man.

Crabs, lobsters, and the like, are liable
30 to discolor, if canned under ordinary proc-
ess. This is due to the sulfurous matter
contained in the blood coagulating with the
flesh of such lobster-crustacean. Such sul-
furous matter, upon decomposition, forms
35 an ammonium sulfid and hydrogen sulfid,
which, upon coming into contact with iron
produce iron sulfid which act so detri-
mentally upon the products as to blacken
them disadvantageously so that they can
40 not be received by the consumer. To ob-
viate this difficulty, heretofore, several
means have been proposed, such as by coat-
ing the inner surface of the cans with

special lacquer, or by providing an insulat-
ing means through the use of acid paper,
bamboo skin, wood shavings, etc. These 45
methods are not satisfactory as it does not
enable the full capacity of the process to
be obtained.

I may carry out my said operation by first
taking off the shell or carapace of the crabs,
lobsters, and the like, while they are not
yet perished, then pinch off each leg, prefer-
ably with a pair of scissors or shears, in
such a manner as to first cut off the first
55 articulations and proceeding to take off the
claws from the fourth articulations of each
leg, and lastly cut off the second and third
articulations in successive order. The body
and legs thus operated on will then be set
aside for several minutes. This will allow 60
practically all containing blood and lymph
to flow out spontaneously through the points
so operated, and leave no source of produc-
ing iron sulfid which act so detrimentally
upon the flesh of the crabs, lobsters, and 65
the like, packed in the tin cans.

Having described my invention what I
claim as new and desire to secure by Let-
ters Patent of the United States, is—

Process for canning crabs, lobsters, and 70
the like, which consists in first stripping off
the carapace and articularly operating upon
each leg of said crabs, lobsters, and the like,
while alive, as to cause the blood and
lymph circulating therein to flow out spont- 75
aneously, and subsequently treating same
in usual manner, substantially as set forth.

In testimony whereof I affix my signature
in presence of two witnesses.

KATSUSABURO USUI.

Witnesses:

GENJI KURIBARA,
HARUTADA YASUMARA.
